CANDLESTICK

Kirkland W. Todd, Pittsburgh, Pa., assignor to
The Jeannette Glass Company, Jeannette, Pa.,
a corporation of Pennsylvania

Application April 7, 1951, Serial No. 14,753

Term of patent 14 years

(Cl. D48—2)

To all whom it may concern:

Be it known that I, Kirkland W. Todd, a citizen of the United States, residing at Pittsburgh, in the county of Allegheny and State of Pennsylvania, have invented a new, original, and ornamental Design for a Candlestick, of which the following is a specification, reference being had to the accompanying drawing, forming a part hereof, wherein:

Fig. 1 is an elevational view of one side of a candlestick showing my new design;

Fig. 2 is a vertical section through the major axis of the candlestick; and

Fig. 3 is a top plan view thereof.

The article is symmetrical, all sides being the same.

I claim:

The ornamental design for a candlestick, substantially as shown and described.

KIRKLAND W. TODD.
